UNITED STATES PATENT OFFICE

AUGUST J. SMITH, OF MOUNT PLEASANT, MICHIGAN, ASSIGNOR TO AMERICAN
ENAMELED PRODUCTS COMPANY, OF CHICAGO, ILLINOIS, A CORPORATION OF
ILLINOIS

DESIGN FOR COMBINATION SOAP DISH AND HANDRAIL

Application filed December 26, 1930. Serial No. 38,127. Term of patent 7 years.

To all whom it may concern:

Be it known that I, AUGUST J. SMITH, a citizen of the United States, and a resident of the city of Mount Pleasant, in the county of Isabella and State of Michigan, have invented a new, original, and ornamental Design for a Combination Soap Dish and Handrail, or Similar Article, of which the following is the specification, reference being had to the accompanying drawings, forming a part hereof.

On the drawings:

Figure 1 is a plan view of a combination

soap dish and hand-rail, showing my new design.

Figures 2 and 3 are front and side elevations respectively of the article shown in Figure 1.

I claim:

The ornamental design for a combination soap dish and hand-rail, as shown.

In testimony whereof, I have hereunto subscribed my name at Mt. Pleasant, Isabella County, Michigan.

AUGUST J. SMITH.
